PLUG FOR TUBES

Walter Wainwright, Brooklyn, N. Y.

Application November 7, 1934, Serial No. 751,896

6 Claims. (Cl. 138—91)

This invention relates to plugs for tubes and more particularly to plugs for boiler tubes.

One of the objects of this invention is to provide a tube plug which will be exceedingly practical in operation and durable in construction and use. Another object is to provide a device of the above nature which will be relatively inexpensive and simple to manufacture. Another object is to provide such a construction which is capable of being conveniently mounted in operative position without the need of undue alterations or adjustments to meet varying conditions. Another object is to provide a construction of the above nature which will be strong and dependable in operation and which may be installed with a minimum of time and expense. Another object is to provide a plug for tubes adapted to close both ends of the tube with a single operation. Another object is to provide a construction of the above nature which may be operated solely from one end of the tube.

Other objects will be in part obvious or in part pointed out hereinafter.

The invention accordingly consists in the features of construction, combination of elements, and arrangements of parts as will be exemplified in the construction to be hereinafter described, and the scope of the application of which will be indicated in the following claims.

In the accompanying drawing in which is shown one of the various possible embodiments of this invention—

Fig. 1 is a longitudinal section through a tube having a plug in accordance with the present invention inserted therein.

Fig. 2 is a similar view showing the plug in its finally adjusted position;

Fig. 3 is an end view of one of the elements embodied in the plug of the present invention.

Similar reference characters refer to similar parts throughout the several views of the drawing.

As conducive to a clear understanding of this invention, it may here be pointed out that boilers embodying tubes are generally of two types, known as the fire tube type and the water tube type. In both types it frequently happens that a leak will occur in one of the tubes. To repair the leaky tube, it is usually necessary to draw the fire from the boiler thus to shut down its operation until repairs have been completed. The instant device contemplates the provision of a plug insertible into a leaky tube whereby such an individual tube may be shut off without the necessity for drawing the fire or discontinuing opera-

tion of the boiler. Devices for this purpose have been previously constructed, but in all such constructions there has been a uniform difficulty in providing a device which may be inserted while the boiler is in operation and which will serve to seal the tube at both ends and in which the closure of both ends may be effected simultaneously from the front and accessible end of the tube. It has been a further difficulty of devices of this nature to provide means which will effectively seal the tube against any leakage whatsoever. It is an object of this invention to overcome these difficulties, as well as others, all as will be apparent from the following.

Referring now to the drawing, 10 indicates the front tube sheet of a conventional boiler; 11 the rear sheet thereof. A single tube such as a tube in need of repair is generally indicated at 12. It will be understood that in any boiler construction there are a plurality of such boiler tubes or flues 15 into any one of which the plug to be described may be introduced. Such a plug may advantageously include a hollow core generally indicated at 13, preferably constructed of steel or any other suitable material. Core 13 comprises a cylindrical sleeve 14 of materially lesser diameter than the tube to be plugged and core heads 15 and 16. Core heads 15 and 16 may be formed integrally with sleeve 14 or may, as shown in the drawing, be threaded upon threaded extremities 17 and 18, respectively, of said sleeve. Preferably the hub portions 15a and 16a of the core heads are formed of irregular shape, such as hexagonal, whereby the heads may be readily turned on the sleeve by a wrench or the like. Each of core heads 15 and 16 has a radially extending flange 19 and 20, respectively, whereby to define apertures or bores 21 and 22, respectively, through which bores passes an operating bolt 23, the structure and purpose of which will be more fully described hereinafter. Each of the core heads 15 and 16 also has a cylindrically extending flange 24 and 25, respectively, the outer diameter of which is made of a predetermined size, slightly less than the diameter of the boiler tube in which the plug is to be inserted. The end faces of flanges 24 and 25 are chamfered as indicated at 24a and 25a, respectively. Flanges 19 and 24 thus form and define a recess 26 in core head 15 and flanges 20 and 25 similarly form and define a recess 27 in core head 16.

It may be here pointed out that core 16 thus forms a single, and for all practical purposes integral, unit adapted to fit within a boiler tube and extend substantially from end to end there-

of. In the construction of the device, core 13 is manufactured in predetermined lengths adapted to be fitted into a boiler tube of given length.

Operating bolt 23 previously mentioned is threaded at its extremities 23a and 23b and is so positioned as to pass through apertures 21 and 22 in core heads 15 and 16 and to be centrally located with respect thereto. Such apertures are of a diameter to provide a sliding fit for bolt 23, and to 10 maintain the core and bolt in axial alignment.

Gaskets 28 and 29 are respectively positioned immediately adjacent chamfered end faces 24a and 25a of core heads 24 and 25. These gaskets, in the preferred embodiment of the invention are 15 constructed preferably of asbestos or like heat-resistant material and are of rectangular cross section having openings 28a and 29a, respectively positioned in the center of the periphery thereof (see Fig. 1). It will be understood, however, that 20 gaskets of any other suitable configuration may be used. Openings 28a and 29a are provided to allow a space for contraction of gaskets 28 and 29 when they are compressed in a manner and for a purpose to be more fully described hereinafter. 25

A pair of gasket retaining rings 30 and 31 are positioned adjacent core heads 15 and 16, respectively. Rings 30 and 31 are preferably cylindrical in form and engage the inner surfaces of the 30 flanges 24 and 25, and also the bottom face of gaskets 28 and 29. The external diameter of rings 30 and 31 is slightly less than the internal diameter of the recesses 26 and 27 in the core heads formed by the flanges, as above noted, 35 whereby rings 30 and 31 may move into said recess.

Threaded on to the threaded end 23a of operating bolt 23 is a nut 32 which, prior to insertion of the plug into tube 12, serves merely to hold the 40 apparatus in assembled relation. Nut 32 is screwed down until it engages the flange 19 and thus serves to hold the operating parts of the mechanism in assembly until tightened to its final adjusted position in a manner to be more 45 fully described hereinafter.

Threaded on to the threaded end portion 23b of operating bolt 23 is a metallic clamping head 33, which may if desired be composed of a suitable 50 heat-resistant material. On the inner surface of head 33 a pair of suitably spaced cam surfaces 33a and 33b are formed. Immediately adjacent head 33 and between head 33 and gasket 29 is an expandable collar 34 (see Fig. 3) composed of a plurality of segments (illustratively three) 34a, 55 34b and 34c, so shaped as to form a disc-like ring when positioned about operating bolt 23 (see Fig. 2 and the full line position of Fig. 3).

Collar 34 serves, when expanded in a manner to be more fully described hereinafter, to protect 60 gasket 29 from direct contact with the flame of the fire to the rear of tube sheet 11, and at the same time binds against the inner tube surface to definitely locate the plug within the tube.

Such expanding action of collar 34 is effected 65 through a cam surface 35 formed about the outer periphery thereof and so positioned as to engage, when the device is in assembled relation, cam surface 33a of clamping head 33 and a second cam surface 36 also formed on ring 34 in such 70 position as to engage the cam surface 33b of head 33. As is better shown in Fig. 2, these cam surfaces are so related that, upon actuation of clamping head 33 relatively toward the front of the boiler tube, in a manner to be hereinafter described, they will coact to cause expansible collar 75

34 to expand and assume the dotted line position shown in Fig. 3, at which time it will closely engage the walls of boiler tube 12.

The angular disposition of these cam surfaces 33a-35, 33b-36, with respect to each other is 5 such, however, that even upon close contraction of clamping head 33 toward collar 34 an air space 37 will be left between collar 34 and clamping head 33. Air space 37 serves as insulation to prevent radiation of heat from the outer surface of 10 head 33 to the segments comprising collar 34 and thence to gasket 29 and consequently provides an additional protection against the burning out of gasket 29.

It may here be noted that of the two gaskets 15 28 and 29, 29 will be subjected to the greatest heat due to the fact that the hottest flame is at the end of tube 12 closed by head 33. Gasket 28 being positioned at the less exposed end of the tube consequently needs no such protection as 20 collar 34.

Portions 38 (see Figs. 1 and 2) are upstruck upon the back of each of segments 34a, 34b, 34c comprising collar 34. About upstruck portions 38 a relatively frangible wire 39 is positioned and 25 relatively tightly contracted (see Figs. 1 and 3). The purpose of this is to provide suitable means for holding collar 34 in its contracted position until it is desired to expand it into its protective position as shown in Fig. 2 and also in the dotted 30 line portion of Fig. 3. When clamping head 33 is drawn towards boiler tube 12, the pressure upon cam surfaces 35 and 36 of collar 34 will cause segments 34a, 34b, 34c to move and expand radially, causing them to assume the dotted line 35 position of Fig. 3. Such pressure will be sufficient to rupture frangible wire 39 and permit expansion of the collar to a degree limited only by the interior diameter of boiler tube 12.

A front clamping head 40 is positioned on 40 threaded end 23a of operating bolt 23 immediately adjacent gasket 28 and its associated retaining ring 30.

Also, upon end 23a of bolt 23, but outside of head 40, a plug finder 41 (see Fig. 1) which may 45 also serve as a guard member is placed. Plug finder 41 is preferably in the form of a circular shield and has a flange 41a extending inwardly towards head 40 located about its outer periphery. Flange 41a extends a material distance in 50 a lateral direction and is so arranged and positioned as to indicate by its abutment against tube sheet 10 the limit to which the plug should be inserted in tube 12. This length will be determined by the particular installation and the 55 length of the plug is predetermined accordingly.

Plug finder 41 also serves as a shield to prevent the escape of flame or hot steam on to the person of the operator during insertion of the device.

A tightening nut 42 is threaded upon the outer 60 end of bolt 23 outside of head 40 and plug finder 41.

In operation the plug is inserted into boiler tube 12 until flange 41a of plug finder 40 engages tube sheet 10. Tightening nut 42 may now be 65 removed to permit removal of the finder 40, if such is desired, and nut 42 is thereupon replaced. Said nut is now turned on the threaded end 23a of bolt 23 so as to draw the two clamping heads 33 and 40 towards each other and towards fixed 70 core heads 15 and 16 respectively. The inward movement of head 33 causes cam surfaces 33a and 33b to coact with cam surfaces 35 and 36, respectively, to expand the individual segments of expansible collar 34 radially, breaking frangible 75

wire 39, and to compress gasket 29 against the chamfered surface 25a of core head 25. Simultaneously as head 40 is forced inwardly, gasket 28 is compressed against the chamfered surface 24a of core head 24. Gasket retaining rings 30 and 31 are moved inwardly into the recesses 26 and 27 of core heads 15 and 16, respectively, and nut 32 is moved outwardly from its abutment with the outer face of flange 19 to a relatively central position in recess 26.

It will thus be seen that any expansion of gaskets 28 and 29 must be outward towards the tube 12, since movement in any other direction is restricted by the core heads, the clamping heads, and the gasket retaining rings. The compressed gaskets thus furnish a complete seal between the ends of the core and the tube, and with core heads 15 and 16 and sleeve 14 forming a unitary, leak-tight structure, leakage from the ends of the tube is prevented and the tube is thus plugged and cut out effectively from operation.

Collar 33 serves to supplement the seal formed by gasket 29 and further serves to protect gasket 29 from direct contact with the hot flame, while air space 37 acts as further insulation to prevent undue heat from reaching gasket 29.

The plug as described is simple in construction and may be readily manufactured. The core heads may be cast with the only machining required being the threads uniting the heads with the sleeves. The majority of the parts of the plug are readily available and may be constructed inexpensively by conventional machine practice. The parts are capable of ready assembly and when assembled may be positioned in a leaky tube in a single operation, following which the rotation of the tightening nut acts to completely seal the tube.

From the foregoing, it will be seen that there is herein provided a device which embodies the features of this invention and achieves the objects thereof including advantages of great practical importance. As many possible embodiments may be made of the above invention and as many changes might be made in the embodiment as above set forth, it is to be understood that all matter hereinbefore set forth or shown in the accompanying drawing is to be interpreted as illustrative and not in a limiting sense.

I claim:

1. A plug for tubes comprising, in combination, a hollow core, a pair of opposed core heads threadedly associated therewith, the length of the core and the core heads being slightly less than the length of the tube to be plugged, said core heads being of an external diameter adapted to fit within said tube and having openings axially disposed therethrough, an operating bolt passing through said openings and said core, clamping heads fitted on the ends of said operating bolt, each operatively related to a core head, compressible gaskets disposed between said core heads and said clamping heads, an expansible collar positioned between one of said clamping heads and its associated gasket, said collar comprising a plurality of segments normally forming a disc-like ring, means normally holding said segments in related assembly, and means to draw said clamping heads toward each other whereby to compress said gaskets against said core heads, and said collar against one of said gaskets, to form a fluid-tight seal at each end of said core, said means being operative to render said holding means inoperative and expand said collar radially to engage the inner circumference of said tube.

2. A plug for tubes comprising, in combination, a hollow core including a pair of opposed core heads, the length of the core being slightly less than the length of the tube to be plugged, said core heads being of an external diameter adapted to fit within said tube and having openings axially disposed therethrough, an operating bolt passing through said openings and said core, clamping heads fitted on the ends of said operating bolt, each operatively related to a core head, compressible gaskets disposed between said core heads and said clamping heads, an expansible collar positioned between one of said clamping heads and its associated gasket, said collar comprising a plurality of segments normally forming a disc-like ring, upstruck portions on the rear surface of each of said segments, frangible retaining means passed about said upstruck segments whereby to retain said segments in contracted position, and means to rupture said retaining means and expand said segments radially whereby to expand said collar, said means being operative to draw said clamping heads toward each other to compress said gaskets against said core heads to form a fluid-tight seal at each end of said core and to compress said collar against one of said gaskets to form a heat protective barrier at one end of said core.

3. A plug for tubes comprising, in combination, a hollow core including a pair of opposed core heads, the length of the core being slightly less than the length of the tube to be plugged, said core heads being of an external diameter adapted to fit within said tube and having openings axially disposed therethrough, an operating bolt passing through said openings and said core, clamping heads fitted on the ends of said operating bolt, each operatively related to a core head, compressible gaskets disposed between said core heads and said clamping heads, an expansible collar positioned between one of said clamping heads and its associated gasket, said collar comprising a plurality of segments normally forming a disc-like ring, upstruck portions on the rear surface of each of said segments, a wire passed about said upstruck segments whereby to retain said segments in contracted position, and means to rupture said wire and expand said segments radially whereby to expand said collar, said means comprising operatively associated cam surfaces on the outer face of said expansible collar and the inner face of its associated clamping head, and means to draw said clamping heads toward each other whereby to compress said gaskets against said core heads to form a fluid-tight seal at each end of said core and to compress said collar against one of said gaskets to form a heat protective barrier at one end of said core.

4. A plug for tubes comprising, in combination, a hollow core including a pair of opposed core heads, the length of the core being slightly less than the length of the tube to be plugged, said core heads being of an external diameter adapted to fit within said tube and having openings axially disposed therethrough, an operating bolt passing through said openings and said core, clamping heads fitted on the ends of said operating bolt, each operatively related to a core head, compressible gaskets disposed between said core heads and said clamping heads, an expansible collar positioned between one of said clamping heads and its associated gasket, said collar comprising a plurality of segments normally forming a disc-like ring, upstruck portions on the rear surface of each of said segments, a wire passed about said

upstruck portions and operative to retain said segments in contracted position, and means to rupture said wire and expand said segments radially whereby to expand said collar, said means comprising a plurality of cam surfaces on the outer face of said expansible collar and a plurality of cam surfaces on the inner face of its associated clamping head, the angular disposition of said cam surfaces on said collar to said cam surfaces on said clamping head being such that upon close contraction and coaction of said cam surfaces an air space is left between said expansible collar and said clamping head, and means to draw said clamping heads toward each other whereby to compress said gaskets against said core heads to form a fluid-tight seal at each end of said core and to compress said collar against one of said gaskets to form a heat protective barrier at one end of said core.

20 5. A plug for tubes comprising, in combination, a hollow core including a sleeve and a pair of spaced core heads threaded thereto whereby to form a fluid-tight seal and to permit a relative adjustability of the length of said core, the normal length of the core being slightly less than the length of the tube to be plugged, said core heads each having a radial flange adapted to partially close the ends of said sleeve, and a circumfer-

tial flange of an external diameter adapted to fit within the tube to be plugged, said flanges intersecting to form a recess, an operating bolt passing through said sleeve and core heads, an assembly nut threaded on said operating bolt and disposed in said recess and operative to abut a face of said radial flange, clamping heads each operatively related to a core head, compressible gaskets disposed between said core heads and said clamping heads, and means cooperating with said bolt to draw said clamping heads toward each other whereby to compress said gaskets against the ends of said circumferential flanges to form a fluid-tight seal at each end of said core. 5

6. A plug for tubes comprising, in combination, 15 a hollow sleeve, a pair of opposed core heads threadedly associated with said sleeve whereby to permit a relative variation of the length of said plug within predetermined limits without disassembly of said plug, clamping heads positioned adjacent said core heads, compressible gaskets disposed between said core heads and said clamping heads and means to draw said clamping heads inwardly towards said core heads to compress said gaskets and seal the ends of said 20 tube. 25

WALTER WAINWRIGHT.
